Primary Examiner — Rashida Johnson*(74) Attorney, Agent, or Firm* — Banner & Witcoff, Ltd.(57) CLAIM

The ornamental design for pants, as shown and described.

DESCRIPTION

FIG. 1 is a front left perspective view of the pants showing our new design;

FIG. 2 is a rear right perspective view thereof;

FIG. 3 is a front view thereof;

FIG. 4 is a rear view thereof;

FIG. 5 is a right side view thereof;

FIG. 6 is a left side view thereof;

FIG. 7 is a front left perspective view of a pant showing an alternative embodiment of the new design;

FIG. 8 is a rear right perspective view thereof;

FIG. 9 is a front view thereof;

FIG. 10 is a rear view thereof;

FIG. 11 is a right side view thereof; and,

FIG. 12 is a left side view thereof.

The uneven-length broken lines within the shaded area represents unclaimed stitching and seams and forms no part of the claimed design. The generally horizontally-oriented even-length broken line region located in the upper-rear portion of the pants represents an unclaimed zipper region and forms no part of the claimed design. The broken lines showing the remainder of the pants are for environmental purposes only and form no part of the claim design. The contrast in stipple shading represents a contrast of appearance and does not represent any particular color, texture, or material. The uneven-length broken line adjacent the bottom of the claimed region represents an unclaimed boundary of the design.
